DESIGN FOR A WASHING MACHINE DOLLY

Sidney S. Holland, Sandusky, Ohio, assignor, by
mesne assignments, to The Apex Electrical
Manufacturing Company, Cleveland, Ohio, a
corporation of Ohio

Application August 10, 1936, Serial No. 64,334

Term of patent 7 years

To all whom it may concern:

Be it known that I, Sidney S. Holland, a citizen
of the United States, residing at Sandusky, in the
county of Erie and State of Ohio, have invented
a new, original, and ornamental Design for Wash-
ing Machine Dollies, of which the following is a
specification, reference being had to the accom-
panying drawing, forming part thereof.

Fig. 1 is a perspective view of a washing ma-
chine dolly, showing my new design.

Fig. 2 is a plan view of the washing machine
dolly.

I claim:

The ornamental design for a washing machine
dolly, as shown.

SIDNEY S. HOLLAND.
